UNITED STATES PATENT OFFICE.

LEWIS E. CURTIS, OF WARREN, OHIO, ASSIGNOR, BY MESNE ASSIGNMENTS, TO A. C. PAUL, OF MINNEAPOLIS, MINNESOTA, AND GEORGE A. CHITTON, OF RIVER FOREST, ILLINOIS, TRUSTEES.

CORNER BEAD.

Application filed November 24, 1923, Serial No. 676,733. Renewed January 24, 1927.

The present invention relates to the manufacture of expanded metal corner beads, and will be fully understood from the following description, illustrated by the accompanying drawings, in which:

Fig. 1 is a plan view of one end of a blank suitable for use in the manufacture of the bead.

Fig. 2 is a plan view corresponding to Fig. 1, showing the same position of the blank provided with a central groove or channel.

Fig. 3 is a sectional view through the blank at the stage shown in Fig. 2, the blank being illustrated between forming dies or rolls, also shown in partial section.

Fig. 4 is a bottom plan view, somewhat diagrammatic, of a die suitable for use in slitting the blank.

Fig. 5 is a partial sectional view through the die on the line 5—5 of Fig. 4.

Fig. 6 is a plan view of the blank at an intermediate stage in the slitting operation, the forward end being shown with marginal ribs.

Fig. 7 is a sectional view of the blank, showing the contour of the marginal ribs or grooves and also showing diagrammatically in section the rib forming dies or rolls.

Fig. 8 shows in end elevation the slitted blank after an initial median bending operation, also showing diagrammatically in section the bending dies or rolls.

Fig. 9 shows the slitted blank in end elevation after the bead forming operation, also showing diagrammatically the bead forming dies.

Fig. 10 is a side elevation of the slitted blank after the bead forming operation.

Figs. 11 and 12 show respectively the initial and final stages of the expanding operation, the expanding dies being diagrammatically shown, and

Fig. 13 is a side elevation of a portion of the expanded corner bead.

In accordance with the present invention, a strip or blank of sheet metal is slit on each side of a defined central area, a median channel being formed in the central area, longitudinally of the blank, prior to the bending of the blank into bead form. In the drawings the formation of this channel is shown

as taking place prior to the slitting operation, this order may, if desired, be reversed. Thus in Fig. 1, the numeral 10 designates the strip or blank, an end portion of which is shown. In Fig. 2, the blank 10 is shown with a median channel 11, of trough-like form, this channel being suitably formed by passing the blank 10 either continuously or step by step through suitable mating dies or rolls 12 and 13, as shown diagrammatically in Fig. 3. In this figure the blank is shown in section, with the trough-like channel 11 formed therein.

The blank is slitted on both sides of a defined central area in which the longitudinal channel is formed either before or after the channel forming operation. In the illustrated embodiment of the process the slitting is shown as following the channel forming operation. The slits formed parallel each other in rows longitudinally of the sheet and are inclined at an angle to the median line thereof, the slits in adjacent rows being inclined reversely to each other, whereby strands of the herring-bone type are formed. In forming the slits the blank is intermittently advanced, a group of a plurality of slits being formed in each longitudinal row after each step of advance movement, the groups of slits in adjacent rows on either side of the defined central area not being transversely aligned; but preferably following each other. In practice the group of slits formed in each row preferably contain the same number of slits and the blank is advanced at each step the length of a group of slits, whereby, on continuing the operation for the length of the blank, the rows of slits extend evenly the length thereof.

Suitable means for carrying the slitting operation into effect are illustrated diagrammatically in Figs. 4 and 5 of the drawings. In Fig. 4 is shown in plan the cutting face of a die 14 in which are mounted groups of slitters 15, inclined to the length of the die. The groups of slitters on either side of the central area contain equal numbers of slitters 15, and those in adjacent rows are not transversely aligned, but follow each other. Thus, on either side of the median line there is a group of slitters in

one longitudinal row, designated A, and immediately following it a group B in the next adjacent row. It will also be noted that, in the preferred form of construction shown in Fig. 4, the transversely aligned slitters are symmetrically disposed with respect to the center line of the die, thereby promoting evenness of operation during slitting.

10 In performing the slitting operation the blank is advanced intermittently the length of a group of slitters in the die at each step. This is continued for the length of the blank, longitudinal rows of parallel inclined slits 17 being thereby formed for the entire length of the blank. In Fig. 6 the blank is shown at an intermediate stage in the slitting operation, the herring-bone arrangement of the strands on each side of the central area being clearly apparent.

After being slit, in the embodiment of the process illustrated, the blank may be passed between suitable dies or rolls 18, 19 by which marginal ribs 20 are formed in the blank, as shown in Figs. 6 and 7. It is readily apparent that, if desired, the marginal ribs may be formed in the sheet prior to the slitting operation, or at any other desired stage of operation.

30 The central area of the blank which is preferably channelled, and on each side of which slits are formed in the manner above described, is shaped to bead form. This may suitably be effected in two stages, as shown in Figs. 8 and 9. The channelled blank is passed between dies or rolls 21 and 22, which bend over the channelled central area of the blank to approximately the desired angle (e. g. 90°), as shown in section in Fig. 8, and is then formed to bead shape, for example, by sliding dies 23, 24 and 25 cooperating with a stationary die 26. These dies shape the central portion of the blank to a bead portion 26 and a stem portion 27, from which the slitted sides project at an angle, the blank at this stage being shown in section in Fig. 9 and in side elevation in Fig. 10.

50 The blank is then expanded, suitable means for this purpose being shown in Figs. 11 and 12. The expanding device may suitably be provided with a central gripping device 29, which engages the bead portion, preferably at the stem portion 28, and side gripping devices 30, which may suitably engage the marginal ribs 20. The side gripping devices are swung to the position shown in Fig. 12 after engaging the blank, thereby expanding the latter by bending and twisting the strands. The completed product is shown in section in Fig. 12, and in side elevation in Fig. 13.

I claim:

65 1. The method of forming an expanded metal corner bead which consists in advanc-

ing a blank longitudinally, forming a central channel therein, forming a plurality of slits in a longitudinal row on each side of said central channel, continuing the advance of the blank and the formation of slits for the length of the blank, shaping the central channel to form a bead and subsequently expanding the slitted portions on each side thereof.

2. The method of forming an expanded metal corner bead which consists in advancing a blank longitudinally step by step a distance of a plurality of slits to be cut therein, forming a central channel therein, after each successive movement of the blank simultaneously forming therein series of longitudinally aligned inclined slits on each side of a defined central area, continuing the advance of the sheet and the formation of slits for the length of the sheet, shaping the central channel to form a bead bending the blank longitudinally to cause the slitted side portions of the blank to form an angle with each other, and subsequently expanding the slitted side portions.

3. The method of forming an expanded metal corner bead which consists in advancing a blank longitudinally step by step a distance of a plurality of slits to be cut therein, forming a central channel therein, after each successive movement of the blank simultaneously forming therein series of longitudinally aligned inclined slits on each side of a defined central area, continuing the advance of the sheet and the formation of slits for the length of the sheet, shaping the central channel to form a bead and to cause the slitted side portions of the blank to form an angle with each other and subsequently expanding the slitted side portions, the margins of the blank being longitudinally ribbed prior to the said shaping operation.

4. The method of forming an expanded metal corner bead which consists in advancing a blank longitudinally step by step a distance of a plurality of slits to be cut therein, forming a central channel therein, after each successive movement of the blank simultaneously forming therein series of longitudinally aligned inclined slits on each side of a defined central area, continuing the advance of the sheet, and the formation of slits for the length of the sheet, shaping the central channel to form a bead and to cause the slitted side portions of the blank to form an angle with each other, and subsequently expanding the slitted side portions, the central area being channelled and the margin being ribbed prior to the said shaping operation.

5. The method of forming an expanded metal corner bead which consists in advancing a blank longitudinally step by step a distance of a plurality of slits to be cut therein, forming a central channel therein, after each

successive movement of the blank simultaneously forming therein series of longitudinally aligned inclined slits on each side of a defined central area, said central area being 5 previously channelled, continuing the advance of the sheet and the formation of slits for the length of the sheet, forming ribs in the outer margins of the blank, shaping the

central channel to form a bead and to cause the slitted side portions of the blank to form 10 an angle with each other and subsequently gripping said central bead and the edges of the sheet and separating them, thereby expanding the slitted side portions.

LEWIS E. CURTIS.
